(57) **CLAIM**

The ornamental design for a nasal spray device, as shown and described.

DESCRIPTION

1. Nasal spray device

1.1 : Perspective

1.2 : Front

1.3 : Back

1.4 : Right

1.5 : Left

1.6 : Top

1.7 : Bottom

The article of manufacture to which the ornamental design has been applied is a nasal spray device that is used in the pharmaceutical field. All broken lines depict portions of the nasal spray device that form no part of the claimed design.

1 Claim, 7 Drawing Sheets
